UNITED STATES PATENT OFFICE

2,122,004

Gertrude L. de Give, Atlanta, Ga.

**Application November 21, 1934, Serial No. 754,155
Renewed November 24, 1937**

4 Claims. (Cl. 281—381)

The present invention relates to a tab attached to an object, said tab to be engaged for permitting quick and convenient movement of the object, and aims to provide a novel and improved device of this character more especially designed for use on pages of sheet music, books, pamphlets and the like so as to facilitate the turning of pages without damaging same, such as tearing or the like.

10 Another object of the invention is the provision of a tab attached to the lower right hand corner of a page of a book or the like, constructed and arranged so as to present the maximum surface for adhesion to the page, without obstructing the printed or reading matter thereon.

A further object of the invention is to provide a tab of tough and durable material, cut and folded so that the natural tendency of a portion thereof is to extend outwardly away from the page for quick and easy engagement thereof.

It is also an object of the invention to provide a tab of the character indicated, which is simple and substantial in construction, which may be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein:—

Figure 1 is a perspective view of a portion of sheet music, showing my improved tab attached to a page thereof,

Figure 2 is a plan view of a blank from which the tab is constructed.

Figure 3 is a plan view of a corner of a page with the tab thereon.

45. Figure 5 is a perspective view of the tab, showing the slot and the notch.

Referring to the drawing the numeral 10 indicates a book, pamphlet, sheet music, or the like, having pages 11 therein. The illustration is of a music book, the pages of which must be turned very quickly during the playing of a musical instrument, so as not to cause interruption in the music being played.

In carrying out my invention, the numeral 12 designates a flat blank of tough and durable ma-

terial, cut with all sides an equal length and in the form of a perfect square. The blank has a fold 13 therein extending in a straight line to opposite corners, dividing the square blank 12 in two triangular portions, the adhesive portion 14 and the engaging tab portion 15.

The under surface of the triangular portion 14 is secured to the page 11 by means of adhesive 16, with the free corner of the portion 14 flush or even with the lower right hand corner of the page 11, as shown in Figures 1 and 3 of the drawing.

By folding the blank in the manner above described the engaging tab portion 15 is arranged above the portion 14, and due to the fact said portions 14 and 15 are of the same piece of material, one folded upon the other, the engaging portion 15 will sit up at an angle from the fold 13 with the free corner thereof away from the corner of the page, which permits easy and quick engagement thereof.

As the entire under surface of the portion 14 of the blank 12 is fixed to the page 11, it can be seen that the maximum amount of surface is present for attaching the tab to the page, without interfering or obstructing the printed matter on the page, as shown in Figures 1 and 3 of the drawing.

Various sheet music is rather expensive, and due to the fact it is necessary to turn the leaves or pages very quickly, often the same are damaged. It is for this reason the present invention will be found very useful, as the same not only relieves the liability of damaging the leaves or pages, but permits the turning thereof quickly so as not to cause improper timing in the music being played. 35

Adhesive 16 may be applied to the triangular portion 14 prior to the marketing thereof, so that the articles may be sold ready to be attached to pages by merely moistening the adhesive and applying slight pressure to the portion 14 and the page. However, it is understood that the articles may be affixed to the pages or leaves when the sheet music, book, pamphlet or the like is sold by the publisher. 40 45

Having thus described my invention, what I claim as new is:—

1. A tab in combination with a leaf of a book or the like, comprising a triangular shaped member, means for attaching one edge of said member to the leaf, with the other two edges free and aligned with the edges of a leaf at a corner thereof.

2. A tab in combination with a leaf of a book 55

or the like, comprising a square blank folded from corner to corner to provide a pair of triangular shaped portions, and means attaching one of said portions to the leaf, with the free edges 5 of each portion parallel and substantially flush with the edges of a leaf at a corner thereof.

3. A tab in combination with a leaf of a book or the like, comprising a square blank folded from one corner to an opposite corner to provide 10 a pair of right angled triangular portions attached together at their acute angled edges caused by forming said fold, and means attaching one of said triangular shaped portions to a

leaf with the right angled edges of each portion adjacent to and parallel with the edges of a leaf at a corner thereof.

4. A tab for facilitating the turning of leaves, comprising a square flat blank folded from one corner to an opposite corner to provide a pair of triangular shaped portions of similar size and formation, one positioned above the other with the free edges of the upper portion flush with the free edges of the lower portion, and a leaf 10 adhering substance on the under surface of the lower of said triangular shaped portions.

GERTRUDE L. DE GIVE.
